UNITED STATES PATENT OFFICE.

JOHN A. MANSON, OF BRIDGEPORT, CONNECTICUT.

CARD-HOLDER.

1,050,742.

Specification of Letters Patent. Patented Jan. 14, 1913.

Application filed November 29, 1911. Serial No. 663,079.

To all whom it may concern:

Be it known that I, JOHN A. MANSON, a citizen of the United States, and a resident of Bridgeport, in the county of Fairfield 5 and State of Connecticut, have invented a new and Improved Card-Holder, of which the following is a full, clear, and exact description.

My invention relates to a new and improved form of card holder, and an object of 10 my invention is to provide a holder for sales cards, which may be readily mounted and which will positively retain the cards in removable position.

With the above and other objects in view, 15 as will more fully hereinafter appear, the present invention consists in certain novel details of construction and arrangement of parts hereinafter fully described, and particularly pointed out in the appended claims.

I attain the above-outlined objects by 20 mounting upon a suitable support, a light metal sheet, the outer edges of which are turned inward on both sides of the sheet, to 25 hold cards upon opposite sides of the same.

Reference is to be had to the accompanying drawings, forming a part of this specification, in which similar characters of reference indicate corresponding parts in all 30 the figures, and in which—

Figure 1 is a front elevation showing a preferred embodiment of my invention mounted upon a suitable support; Fig. 2 is an enlarged transverse sectional view taken 35 on the line 2—2 and looking in the direction of the arrow, portions of said view being broken away centrally, and Fig. 3 is an enlarged horizontal transverse sectional view taken on the line 3—3 looking in the 40 direction of the arrow, also having the central portion broken away.

Described more in detail, I have shown a suitable support A, pivotally mounted upon which is a card holder B, more particularly 45 forming the subject-matter of my invention, which card holder in this instance, is shown to be attached to a support A, by means of a pivoted rod C, having the lower end mounted in a pocket D, and the upper end 50 within a bracket E.

The card holder B comprises a relatively long rectangular sheet 4, preferably of a light metal, the top edge 5 of which is overlapped, as shown more particularly in Fig. 2, to form a bead edge. The outer longitudinal edge 6, as shown more particularly in Fig. 3, is first bent forwardly, as shown at 7, and then bent back upon itself, to form a flange 8; the portion forming the flange is then bent back upon itself again, and is then bent in a plane at right angles to the plane of the sheet 4, to form a side 9, and is then again bent to form a flange 10 on the side opposite to the flange 8, to retain the card on the back of the plate. Preferably, 55 the extreme edge is bent back upon itself, to form a rounded edge 11. The bottom edge 12 is similarly constructed, as shown more particularly in Fig. 2, in order to form a bottom supporting ledge on opposite sides 60 of the sheet 4. The inner edge 13 is similarly bent, except that at spaced-apart points, the side 9 has portions 14 bent outwardly, to encircle and firmly embrace the rod C, forming a plurality of keepers, to 65 maintain the holder on the rod. If desired, the portions 14 may be indented, to positively retain the holder in position. It will be seen by this construction, that the cards 70 F may be inserted from the top between the pairs of flanges 8 or 10, and will rest upon the lower flange at the edge 12, and they 75 may be retained in position by means of pivoted fingers 15.

Should it be desired to hang the card 80 holder upon a suitable pin, an aperture 16 is provided adjacent the upper edge of the holder.

Having thus described my invention, I claim as new and desire to secure by Letters 85 Patent:

1. A card holder, comprising a flat plate having its bottom edge bent to form ledges at opposite sides, and its side edges, each bent to form an inwardly extending flange 95 at each side of the plate and a member connecting said flanges, the connecting member at one edge of the plate being bent at intervals to form pintle keepers or sockets.
2. A card holder, comprising a flat me- 100

2
talic sheet, one edge of which is bent forward over one face of said sheet and then bent back upon itself, overlapping the opposite face of said sheet, and a supporting pivoting rod, spaced-apart portions of said bent back edge encircling said rod.

5 In testimony whereof, I have signed my

name to this specification in the presence of two subscribing witnesses.

JOHN A. MANSON.
